EDWARD B. ALLEN, OF BRIDGEPORT, CONNECTICUT, ASSIGNOR TO THE SINGER
MANUFACTURING COMPANY, A CORPORATION OF NEW JERSEY.

STITCHED BUTTONHOLE.

1,040,839.

Specification of Letters Patent.

Patented Oct. 8, 1912.

Application filed June 20, 1911. Serial No. 634,284.

To all whom it may concern:

Be it known that I, EDWARD B. ALLEN, a citizen of the United States, residing at Bridgeport, in the county of Fairfield and 5 State of Connecticut, have invented certain new and useful Improvements in Stitched Buttonholes, of which the following is a specification, reference being had therein to the accompanying drawings.

10 In stitching buttonholes by machine, it has long been common to lay a cord within the edge-covering overseam stitches upon either the upper or lower face of the fabric, the cord within the overseam having been 15 cut from the supply subsequently to stitching, so as to leave loose ends thereof at one of the extremities of the buttonhole, as in the production of buttonholes for cloth work, or the cords applied to the lower face of the 20 work have been led into and out of the initial and final overseam stitches to connect with those of the adjacent buttonholes of a series upon the lower or unexposed face of certain articles in leather work, such as 25 shoes.

One of the chief objects of applying a corded overseam to the edges of a buttonhole slit with the cord upon the upper side or face of the material is to improve the 30 appearance of the work by giving the overseam a body so as to simulate a bead or ridge around the edge of the buttonhole slit while the margin of the slit is effectively covered, even with the overseam stitches 35 comparatively widely spaced.

While certain of the described advantages have been secured heretofore by the employment of a corded overseam, the buttonhole has been seriously marred in appearance by the protruding cut ends of the cord upon the face of the fabric, and it is the object of the present invention to produce a buttonhole with the edges of the slit 40 covered by a corded overseam with the extremities of the cord wholly confined within the overseam and entirely concealed by the same.

According to the present invention the buttonhole is formed with an overseam extending along both edges and embracing a cord whose extremities are confined within and concealed by the overseam.

The invention further includes a buttonhole formed with an overseam overlying 55 both faces, a cord with concealed extremities

being embraced by said overseam upon one face of the fabric and a cord with its end portions extending through and beyond the ends of the overseam being embraced within the latter upon the opposite face of the 60 fabric.

The invention will be understood by reference to the accompanying drawings, in which—

Figure 1 is an upper face view of a portion of fabric provided with a buttonhole embodying the present invention, and Fig. 2 an enlarged perspective view of the same. Fig. 3 is an under side view of a portion of fabric containing two buttonholes embodying the present invention and showing the lower cords embraced by the overseam and led laterally through and beyond the extremities thereof in a manner well known. 65 70 75

The buttonhole of the present improvement is or may be produced by the employment of the buttonhole stitching and cord-handling devices forming the subject of my pending application Serial No. 632,332, filed June 10, 1911. As represented in the drawings, the fabric 1 is provided with the buttonhole slit 2 with enlarged or eyelet portion 3 whose margins are covered by the overseam, formed in the present instance of interlooped upper thread *a* and lower 80 85 thread *b*.

As represented in the drawings, the overseam is produced by a stitch-forming mechanism comprising a jogging needle in conjunction with threaded and non-threaded loopers. The needle makes an initial descent through the fabric carrying with it a depth-stitch loop *a'* of its thread which is detained while the needle rises and descends through the slit to pass an edge-stitch loop 90 95 *a''* of its thread through the previous depth-stitch loop *a'*, the edge-stitch needle-thread loop being entered by the threaded looper which passes through the same a loop *b'* of lower thread which is distended for passage 100 of the needle in its next depth-stitch thrust in which it carries the succeeding depth-stitch loop through the fabric. The buttonhole is herein represented as of the eyelet-end type, with long barring stitches *s* arranged across the narrow end with the extremities of the stitches in alignment with the depth needle-punctures of the side-stitches. 105

The machine represented in my pending 110

application Serial No. 632,332, before mentioned, is constructed to produce by a continuous operation series of edge-covering overseam stitches and connected barring 5 stitches, so that the latter have their component threads continuous with those of the edge-covering stitches.

As represented in Figs. 1 and 2, the upper or needle-thread *a* overlies the margin of the 10 fabric around the buttonhole slit and interposed between the same and the upper face of the fabric is the cord *c* which follows the contour of the buttonhole slit and is shown as having its extremities *c'* terminating beneath 15 the limb of the upper-thread *a* extending between respectively the first and last depth-stitch needle-punctures and the adjacent edge-stitch loops *a'*. While this is the preferable arrangement, it is obviously 20 immaterial whether the extremities of the cord lie beneath any of the first or last few of the edge-covering stitches or beneath the barring stitches, in case the buttonhole is of the barred-end type. The improvement 25 is obviously applicable to straight buttonholes in which the edge-covering stitches extend in parallel lines throughout the length of the buttonhole whose ends are reinforced by barring or other stitches.

30 As represented in Fig. 3, the under face of the material is provided with a second cord *d* which extends laterally from the left across the closed extremity of the first buttonhole slit and along its right-hand edge, 35 around the eye and thence along the left-hand edge where it crosses the first section and is led across the closed end of the adjacent buttonhole and along its right-hand edge and around the remainder of the slit as 40 previously described. In the completed buttonhole, the initial portion of the cord enters and emerges from the adjacent ends of the covering overseam by which it is embraced, the portions at the extremity of the buttonhole being overlaid by the barring stitches *s* 45 from which the under thread *b* is led to the initial covering stitch of the adjacent buttonhole.

The edge-covering stitches are shown in

the drawings spaced farther apart than 50 they would be in actual practice for the purpose of illustration, but as actually produced, they may be much more widely spaced with the cord upon the face of the fabric than without the latter, in order to give the required effect, and this condition involves economy in both the time and thread required in the production of the buttonhole, while it is found that a cheap cotton cord may be readily used to advantage where a 60 silk covering thread is required without producing a contrast which is detrimental to the appearance of the buttonhole. The covering stitches are herein shown and described as of the two-thread chain-stitch 65 type, but the specific character of the overseam and the method of making the same are obviously immaterial to the present improvement.

Having thus set forth the nature of the 70 invention, what I claim herein is:

1. A fabric having a stitched buttonhole comprising an overseam extending along both edges and around an end of the same, and a cord embraced within said overseam 75 and overlying the outer or exposed face of the fabric and having its extremities at the opposite end of the buttonhole covered and concealed by said overseam.

2. A fabric having a stitched buttonhole 80 comprising a continuous overseam extending along both edges and across an end of the same, and a cord embraced within said overseam and overlying the outer or exposed face 85 of the fabric with its extremities at the opposite end of the buttonhole covered and concealed by overseam stitches whose component threads are continuous with those of the adjacent stitches along the edges of the buttonhole.

In testimony whereof, I have signed my name to this specification, in the presence of two subscribing witnesses.

EDWARD B. ALLEN.
